HOSE

Oscar C. Stahl, Los Angeles, Calif., assignor, by mesne assignments, to The Borden Company, New York, N. Y., a corporation of New Jersey

Application April 4, 1955, Serial No. 35,356

Term of patent 14 years

(Cl. D43—1)

FIG. 2

Fig. 1 is an elevational view of a hose, embodying my new design, with a portion of the center shown broken away to indicate indeterminate length; and

Fig. 2 is a cross-section taken at line 2—2 of Fig. 1.

The essential features of my design reside in the portions shown in full lines.

I claim:

The ornamental design for a hose, as shown and described.
